UNITED STATES PATENT OFFICE.

OLOF OHLSSON, OF NEWARK, NEW JERSEY.

DESIGN FOR A BOTTLE.

SPECIFICATION forming part of Design No. 27,291, dated July 6, 1897.

Application filed March 1, 1897. Serial No. 625,673. Term of patent 14 years.

To all whom it may concern:

Be it known that I, OLOF OHLSSON, a citizen of the United States, residing in Newark, county of Essex, and State of New Jersey, 5 have invented a new and original Design for Bottles, of which the following is a specification.

This invention relates to a design for bottles primarily intended for use in testing milk.

10 In the accompanying drawings, forming part of this specification, Figure 1 is a side elevation of a bottle embodying my invention, and Fig. 2 is a plan view of such bottle.

a is the body of the bottle.

15 *b* is the top, which tapers gradually upward till it meets the graduated neck *c*. The neck *d* passes through the top *b* and down into the body *a* toward the bottom of the bottle. The neck *c* rises higher from the top than the 20 neck *d*.

This description taken in connection with the accompanying drawings is sufficient to convey to any one a clear understanding of the invention and to enable such person to embody my invention. The essential feature 25 of the design is the top having the two necks *c* and *d*.

What I claim as new, and desire to secure by Letters Patent, is—

The design for a bottle substantially as 30 shown and described.

In testimony whereof I have signed my name to this specification in the presence of two subscribing witnesses.

OLOF OHLSSON.

Witnesses:

THOMAS C. PROVOST,
MARGARET L. ROWLAND.
